UNITED STATES PATENT OFFICE.

HOWETH T. FORD, OF CENTRAL VALLEY, NEW YORK.

WASHING DEVICE FOR AUTOMOBILES.

1,096,704.

Specification of Letters Patent.

Patented May 12, 1914.

Application filed January 15, 1914. Serial No. 312,257.

To all whom it may concern:

Be it known that I, HOWETH T. FORD, a citizen of the United States, and a resident of Central Valley, in the county of Orange and State of New York, have invented a new and Improved Washing Device for Automobiles, of which the following is a full, clear, and exact description.

This invention relates to a washing device which is in the nature of an attachment for a hose nozzle, and includes means for holding a sponge which may be used for cleaning vehicle wheels, bodies and the like.

The invention has for its general objects to improve and simplify the construction of washing devices of the character referred to so as to be reliable and efficient in use, comparatively inexpensive to manufacture, of durable and substantial design and readily manipulated so that it can be adjusted to a position of use or disuse.

Another object of the invention is the provision of a sponge holding device which is so constructed as to be applied as an attachment to a hose nozzle and is capable of being adjusted so that the sponge will be directly in line with the stream of water passing from the nozzle, whereby the sponge holder can be thrown to an inoperative position to one side of the nozzle for permitting the stream from the latter to be played directly on the parts to be washed. Obviously the attachment is especially adapted for washing automobiles, but it can be employed for other cleaning operations.

With such objects in view, and others which will appear as the description proceeds, the invention comprises various novel features of construction and arrangement of parts such as will be set forth with particularity in the following description and claims appended hereto.

In the accompanying drawings, which illustrate one embodiment of the invention, and wherein similar characters of reference indicate corresponding parts in all the views, Figure 1 is a side view of the sponge holding attachment applied to a hose nozzle; Fig. 2 is a side view of the holder removed from the nozzle and with the sponge detached; Fig. 3 is a plan view of the sponge clamping means; and Fig. 4 is a detail sectional view of one of the prongs, showing the manner of gripping the sponge.

Referring to the drawing, A designates an ordinary stream or spray nozzle for a

hose B, and to this nozzle is applied the attachment or holder C that clamps a sponge or equivalent cleaning medium D. The holder C includes a clip 1 which embraces the nozzle A and is fastened in place by a bolt 2 that extends through the ends 3 of the clip. This bolt forms a pivot for a frame which consists of two supporting members 4 which extend outwardly from the clip 1 and carry a ring 5 which forms the base of the sponge-clamping means. This ring has outwardly-extending lugs 6 spaced apart around the ring, and in each lug is a sponge-engaging jaw or prong 7. These prongs are shown as connected to lugs 6 by pivots 8, and they may be provided with springs 9 so arranged as to force the prongs inwardly toward each other. The springs resist the outward movement of the prongs and when the sponge is applied the prongs must be thrown outwardly so as to permit the sponge to be placed between the pointed tips 10 of the prongs, and after the sponge is thus positioned the prongs are released so that they can enter the sponge, as clearly shown in Figs. 1 and 4.

To retain the holder in such position that the sponge B will be directly in line with the axis of the nozzle so as to receive a stream of water therefrom, a chain or equivalent element 11 embraces the nozzle A. The end 12 of the chain is fastened to the frame of the attachment by a bolt 13 which extends through the members 4, and the other end 14 of the chain is adapted to be hooked over the extremity 15 of the bolt. Thus the chain and bolt coöperate to form means for embracing the nozzle, so that the sponge holding structure cannot swing to the right or left, Fig. 1, as long as the chain is engaged with the end 15 of the bolt. When it is desired to no longer use the sponge the last link 14 of the chain is unlocked from the extremity 15 of the bolt so that the sponge-holding structure can be swung to the left, Fig. 1. With a sponge-holding device of this character it is to be understood that the user grasps the nozzle of the sponge which forms a handle, whereby the device is used for cleaning the body, wheels and other parts of the vehicle, the sponge being stably held by the attachment. It is unnecessary for the user to place his hands in water, as is necessary with a bucket and sponge method of washing.

From the foregoing description taken in

connection with the accompanying drawings, the advantages of the construction and method of operation will be readily understood by those skilled in the art to which the invention appertains, and while I have described the device which I now consider to be the best embodiment thereof, I desire to have it understood that the device shown is merely illustrative, and that such changes may be made when desired as are within the scope of the appended claims.

Having thus described my invention, I claim as new and desire to secure by Letters Patent:

- 15 1. A device of the class described comprising a nozzle-engaging element, a frame, a sponge-gripping means on the frame, and means for pivotally connecting the frame to the element for permitting the frame to move as a unit for throwing the sponge into and out of alinement with the nozzle to which the device is attached.
- 20 2. A device of the class described comprising a nozzle-embracing clip including a fastening bolt, a frame pivotally attached to the clip by the bolt, and sponge-holding means carried by the frame.
- 25 3. A device of the class described com-

prising a nozzle-embracing clip including a fastening bolt, a frame pivotally attached to the clip by the bolt, sponge-holding means carried by the frame, and means on the frame for releasably embracing the nozzle at a point spaced from the bolt.

4. A washing device comprising an attaching element, a frame pivotally mounted on the element and including a ring, and spring-actuated sponge-holding members mounted on the ring.

5. A device of the class described comprising a clip including a bolt, a frame pivotally connected with the clip through the bolt, sponge-gripping means on the frame, and a nozzle-embracing means carried by the frame, such embracing means including a bolt, and a flexible element having one end fastened to the bolt and the other end detachably connected therewith.

In testimony whereof I have signed my name to this specification in the presence of two subscribing witnesses.

HOWETH T. FORD.
